WATER SPRINKLING DEVICE

Filed Dec. 6, 1927

INVENTOR

GEORGE A. WILLIAMS
By *Martin P. Smith*,
ATTORNEY

UNITED STATES PATENT OFFICE

GEORGE A. WILLIAMS, OF LOS ANGELES, CALIFORNIA

WATER-SPRINKLING DEVICE

Application filed December 6, 1927. Serial No. 238,001.

My invention relates to a water sprinkling device and has for its principal object the provision of a relatively simple, practical and efficient sprinkling device that may be utilized 5 as a connecting member between two sections of water conduit such as hose or pipe, thereby enabling a plurality of the sprinkling devices to be located in a line of hose or the like with the result that water may be sprinkled 10 simultaneously at different points on a lawn or in a garden or orchard,—further to provide a sprinkling device having an adjustable member that functions as a combined valve for controlling the discharge of water from 15 the jet orifice and as a prong to enter the ground and anchor the device, and further to provide a sprinkling device having a water jet deflecting member that is positioned over the jet orifice so as to break up and spray 20 the water throughout a comparatively wide area.

A further object of my invention is to provide a water sprinkling device of the character referred to that is relatively simple in construction, inexpensive of manufacture and which may be advantageously employed in connection with water conduits such as hose and pipes for the efficient spraying of water 25 throughout a comparatively wide area of ground surface.

With the foregoing and other objects in view, my invention consists in certain novel features of construction and arrangement of parts that will hereinafter be more fully described and claimed and illustrated in the accompanying drawing, in which—

Fig. 1 is a side elevational view of a water sprinkling device of my improved construction.

Fig. 2 is an end elevational view of the device.

Fig. 3 is a top plan view.

Fig. 4 is a vertical longitudinal section taken on the line 4—4, of Fig. 3.

Referring by numerals to the accompanying drawing, which illustrates a practical embodiment of my invention,—10 designates a tubular member preferably formed of metal and which constitutes the body of the 50 sprinkler, one end of said tubular body being

provided with an external thread 11, and the other end being internally threaded as designated by 12, and this portion of the body is provided with externally arranged flat faces 13 that are adapted to receive a wrench or 55 light tool that may be utilized when the device is connected to the end portions of hose or pipe sections.

The central portion of the tubular body 10 is provided on its top with an integral disk 60 shaped body 14 in the top of which is formed a recess 15 and formed integral with this disk at the center thereof and within the recess is a short upwardly projecting lug 16. Formed through this lug and the wall of the 65 body 10 is an aperture 17 that functions as a jet opening for the water that discharges from the device, and the lower end of this aperture is reamed to form a tapered seat 18.

Formed through the lower portion of the 70 body 10 and diametrically opposite from the jet opening 17 is a threaded aperture 19, which receives the threaded portion 20 of a rod 21. The upper portion of this rod or that portion above the threaded portion 20 extends 75 diametrically across the opening through tubular member 10 and the upper end of said rod is tapered to form a valve 22 that is adapted to engage on the seat 18 and close 80 the jet opening 17.

The lower end of rod 21 is pointed as designated by 23 and said rod between its pointed lower end and the threaded portion 20 is bent laterally to form a short crank 24, which may be manually engaged when the rod is rotated 85 so as to adjust its upper end toward or away from the seat 18.

By pointing the lower end of the rod the latter may be utilized as a spike or prong that is inserted in the ground, thus anchoring the 90 sprinkling device at any desired point.

Removably seated in the bottom of the recess 15 in disk 14 is a disk 25 preferably formed of suitable sheet metal, said disk being retained in the recess by a snap or split 95 ring 26 that is inserted in a groove 27, the latter being formed in disk 14 just above the edge of the disk 25, and the central portion of said disk 25 is cut for approximately three-quarters of a complete circle, and that por- 100

- tion 28 of the material within this cut is pressed upwardly so as to occupy an inclined plane of approximately 45° directly above the jet opening 17, and thus said upwardly bent portion 28 functions as an inclined deflector to break up and spray the jet of water that strikes against its under surface, and thus said spray is deflected upwardly and outwardly away from the sprinkling device.
- 10 When the central portion of the disk 25 is bent upward to form the inclined deflector the same is bent transversely so as to provide a concave under surface, and thus the water spray that is deflected by the inclined member 15 28 will be discharged throughout a comparatively wide area in one general direction, rather than radially in all directions, and which provision permits a person to approach the sprinkling device and adjust or shift the 20 position thereof without receiving any of the spray that discharges from the device.
- The rod 21 in addition to serving as a spike or prong for anchoring the sprinkling device to the ground at any desired point may be 25 manipulated so as to open or close the jet opening 17, and consequently enabling the jet of water that discharges through said opening to be accurately controlled and regulated.
- 30 A very desirable feature of my invention is the construction that permits the device to be located between hose or pipe sections, for by such arrangement water may be simultaneously sprayed at different points on a 35 lawn or in a garden. By closing or plugging one end of the tubular body 10 and connecting the other end to a section of hose or pipe, the sprinkling device may be utilized at the end of a water conducting line, and it may 40 be held in the hand during sprinkling or spraying operations or anchored to the ground by means of a spike or prong.
- In some instances it may be found advan- 45 tageous and desirable to form the ends of the body 10 similar to the ends of an ordinary hose coupling, and when these end portions are inserted in the adjacent ends of hose sections and clamped thereto in the ordinary manner, the device functions as a combined 50 hose coupling and sprinkler.
- It will be readily understood that minor 55 changes in the size, form and construction of the various parts of my improved water sprinkling device may be made and substituted for those herein shown and described without departing from the spirit of my invention, the scope of which is set forth in the appended claims.
- I claim as my invention:
- 60 1. A sprinkling device comprising a tubular member provided intermediate its ends with a jet opening, an inclined deflector positioned on the tubular member above said jet opening, a rod adjustably seated in said tubular member opposite said jet opening,

the inner end of which rod is adapted to close said jet opening, and the outer end of which rod is pointed.

2. A sprinkling device comprising a tubular member provided intermediate its ends with a jet opening, an inclined deflector positioned on the tubular member above said jet opening, a rod adjustably seated in said tubular member opposite said jet opening, the inner end of which rod is adapted to close said jet opening, the outer end of which rod is pointed, and a portion of which rod is bent to form a crank.

3. A sprinkling device comprising a tubular member having threaded ends, there being a jet opening formed through the wall of said tubular member intermediate its ends, an inclined deflector removably positioned on the tubular member above said jet opening, a member screw seated in the wall of the tubular member opposite said jet opening and adapted when screwed inwardly to close said jet opening, and the outer end of which screw seated member is pointed.

4. A sprinkling device comprising a tubular member having threaded ends, there being a jet opening formed through the wall of said tubular member intermediate its ends, an inclined deflector removably positioned on the tubular member above said jet opening, a member screw seated in the wall of the tubular member opposite said jet opening and adapted when screwed inwardly to close said jet opening, the outer end of which screw seated member is pointed, and a portion of which screw seated member is bent to form a crank.

5. In a water sprinkling device, a tubular member provided intermediate its ends with a jet opening, a disk mounted to rotate freely on top of said tubular member, means for retaining said disk in position on top of said tubular member, the central portion of which disk is pressed upwardly to form an inclined deflector that is positioned above the jet opening in said tubular member, a rod adjustably seated in the bottom of the tubular member opposite said jet opening, the inner end of which rod is adapted to close said jet opening, and the outer end of which rod is pointed.

6. In a water sprinkling device, the combination with a tubular member provided intermediate its ends with a jet opening, an upstanding circular flange surrounding said jet opening, there being a groove formed in the inner face of said flange a short distance above the surface of the chamber within said flange, a disc mounted to rotate freely on the surface of the tubular member within said flange, the edge of which plate is positioned beneath the groove in said flange, the central portion of said plate being cut and pressed upwardly from the marginal portion of said plate to form an inclined deflector that is

positioned above the jet opening in said tubular member and a split snap ring removably positioned in the groove in said flange for retaining the disc and its inclined deflector in position upon the tubular member.

5 In testimony whereof I affix my signature.
